Primary Examiner — Mary Ann Calabrese*Assistant Examiner* — Katelin G Kloberg(74) *Attorney, Agent, or Firm* — Studebaker & Brackett PC(57) **CLAIM**

The ornamental design for a headlight for motor vehicle, as shown and described.

DESCRIPTION

FIG. 1 is a first perspective view of a headlight for motor vehicle;

FIG. 2 is a second perspective view thereof;

FIG. 3 is a front view thereof; and,

FIG. 4 is a left side view thereof.

The broken lines depict portions of the headlight for motor vehicle in which the design is embodied that are not considered part of the claimed design.

1 Claim, 4 Drawing Sheets(56)
